FUSE BOX

Filed Jan. 27, 1928

Inventor

Edgar B. Green.

By Clarence A. O'Brien, Attorney

UNITED STATES PATENT OFFICE.

EDGAR B. GREEN, OF WASHINGTON, DISTRICT OF COLUMBIA, ASSIGNOR OF ONE-HALF TO GEORGE H. CALVERT, JR., OF WASHINGTON, DISTRICT OF COLUMBIA.

FUSE BOX.

Application filed January 27, 1928. Serial No. 249,930.

The present invention relates to a fuse box and has for its prime object to provide a structure for use with household electric appliances which are apt to cause the blowing out of the fuse in the house when too great a load is placed thereon. I have in mind such appliances as electric vacuum cleaners, electric washing machines and the like which are now commonly in use in a great number of households.

A further important object of the invention resides in the provision of a fuse box of this nature which may be conveniently engaged in the wall outlets now commonly provided in residences and the like.

A still further very important object of the invention resides in the provision of a fuse box of this nature which is exceedingly simple in its construction, inexpensive to manufacture, easy to assemble and disassemble and to renew the fuses therein, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a longitudinal section through the fuse box embodying the features of my invention,

Figure 2 is a longitudinal section taken substantially on the line 2-2 of Figure 1,

Figure 3 is an end elevation thereof,

Figure 4 is a transverse section taken substantially on the line 4-4 of Figure 1,

Figure 5 is a plan view of the fuse box showing a portion of a plug in section, and

Figure 6 is a perspective view of one of the contacts.

Referring to the drawing in detail it will be seen that the letter A denotes generally a casing formed with a bottom 5, side walls 6, end walls 7 and 8, and a hinged cover 9 formed with flanges 10 on the sides thereof and one end thereof, the other end being the pivoted end and being mounted by means of pivots 11 engaged in the side walls 6 and the side flanges 10. A flange 12 rises from the pivoted end of the cover 9 to be flushed with the end 7 when said cover 9 is closed. A

plate of insulating material 14 is mounted 55 in the casing C on the bottom 5. A block of insulating material 15 projects through an opening 16 in the wall 8 and is limited in its outward projection by a shoulder 17 formed on said block. This block is provided with an inwardly and vertically disposed rib 18 extending from its inner face. The block is further provided with a centrally located opening 19 extending through the rib 18 and merging at its outer end in a recess 20. The block 15 is further provided with openings 21 one to each side of the opening 19 and recess 20. A block 23 extends through an opening 24 in the end wall 7 and is limited in its projection therethrough 70 by a shoulder 25. This block 24 is formed with a vertically disposed inwardly extending rib 26 which has a central opening 27 therein also extending through the center of the block 23. The block 23 is provided 75 with openings 28 one to each side of the opening 27.

A plurality of contact members T and T' are mounted on the plate 14 by means of screws 30. Each contact member comprises 80 a U-shaped portion 31 the legs of which are curved to form clip jaws for holding the end of a fuse cartridge 32. These U-shaped portions 31 are formed integrally on the ends of horizontal portion 33 which merges into a 85 riser 34 terminating in prongs 35. The prongs of the contact T' are bifurcated as indicated at 36 at their ends. The screws 30 extend through openings in the bight of the U-shaped portion 31 while the prongs 35 90 project through the openings 21 and 28. The bifurcated ends 36 of the contact T' are housed within the openings 21 while the prongs of the contact T extend outwardly beyond the block 33. A rod or bolt 37 extends through the opening 19 having a head 38 at one end in the recess 20 and a shoulder intermediate its ends as at 39 thus limiting the movement of the rod or bolt 37 through said opening 19. This rod 37 also extends 100 through the opening 27 and terminates in a threaded end 40 to the outside of the block 23. A screw plug 41 is adapted to receive the prongs 35 of the contact T and is anchored on the casing by means of a nut 42 embedded 105 in the plug 41 and threadedly engaged with the end 40.

It will be obvious that the cartridge fuses

32 span the contacts T and are detachably held in place by the clip jaws of the U-shaped portions 31.

To assemble the device the block 15 is first inserted in the opening 16 with the block 23 on the rod 37 but pushed adjacent the shoulder 39. When the block 15 is in place it will be seen that the block 23 may be slid along the bolt and inserted in the opening 24. Obviously the contact T may then be assembled and the risers 34 will abut the inner surfaces of the blocks 15 and 23 to prevent them from moving inwardly. The plug 41 should be engaged by nut 42 on the end 40 of the rod 37 before contacts T are put in place. When the plug 41 is screwed in the socket of the base board it will be seen that the flange 12 will abut the base board when the cover 9 is attempted to be opened thus preventing children tampering with the device when in use.

It is thought that the construction, operation and advantages of the invention will be quite apparent without a more detailed description of the construction. The plug 25 of the electric appliance, such as a vacuum cleaner may be engaged in the block 15 by the prongs engaging the bifurcated terminals 36 of contacts T'. Should too much of a load be placed on vacuum cleaner this would tend 30 to blow out the fuses in this fuse box first thus preventing the blowing out of the fuse in the usual fuse box provided in the house or building. The present embodiment of the invention has been disclosed in detail merely 35 as an exemplification of the invention as it has proved practical. It is to be understood, of course, that changes in the details of construction, and in the combination and arrangement of parts may be resorted to without departing from the spirit or scope of the invention as hereinafter claimed or sacrificing any of its advantages.

Having thus described my invention, what I claim as new is:

45 1. A fuse box of the class described comprising a casing, contacts in the casing having clip portions for receiving cartridge fuses, and electrical connection means on the ends of the casing for said contacts, a cover 50 hingedly mounted on the casing and having a flange projecting from the hinged end thereof outwardly for engaging a wash board or

the like to prevent opening of the cover when the box is electrically engaged in a wall socket or the like.

55

2. A fuse box of the class described comprising a casing, contacts in the casing, means insulating the contacts from the casing, said contacts having clip portions to receive the ends of cartridge fuses, said contacts having prongs projecting therefrom, insulating blocks in the casing for receiving the prongs, said blocks extending through openings in the casing and having shoulders to limit their outward projections, said contacts having portions abutting the inner ends of the block to prevent their inward movement.

60

3. A fuse box of the class described comprising a casing, contacts in the casing, means insulating the contacts from the casing, said contacts having clip portions to receive the ends of cartridge fuses, said contacts having prongs projecting therefrom, insulating blocks in the casing for receiving the prongs, said blocks extending through openings in the casing and having shoulders to limit their outward projections, said contacts having portions abutting the inner ends of the block to prevent their inward movement, a rod extending through the block, a plug receiving 75 prongs at one of the blocks and having a nut therein with which the rod is threadedly engaged.

70

4. A fuse box of the class described comprising a casing, contacts in the casing, means insulating the contacts from the casing, said contacts having clip portions to receive the ends of cartridge fuses, said contacts having prongs projecting therefrom, insulating blocks in the casing for receiving the prongs, 80 said blocks extending through openings in the casing and having shoulders to limit their outward projections, said contacts having portions abutting the inner ends of the block to prevent their inward movement, a rod extending through the block, a plug receiving 85 prongs at one of the blocks and having a nut therein with which the rod is threadedly engaged, said rod having a head on the other 90 end thereof and a shoulder intermediate its ends to limit its movement in respect to the other block.

95

In testimony whereof I affix my signature.
EDGAR B. GREEN.
